CIGAR LIGHTER

Arthur A. Johnson, Bridgeport, Conn., assignor to
 Automatic Devices Corporation, Bridgeport,
 Conn., a corporation of Connecticut

Application April 24, 1937, Serial No. 138,801

13 Claims.

(Cl. 219—32)

This invention relates to electric cigar lighters of the type including a holder, and an igniting unit storable on the holder and wholly removable therefrom for use, the igniting unit having a heating element adapted to be brought to incandescence whenever it is desired to prepare the unit for removal and use.

In previously proposed lighters of this kind, in order to provide a practical and conveniently operable lighter wherein neither holder nor unit contained manually relatively movable parts, the arrangement has had to be such that the igniting unit could be shifted back and forth between two positions on the holder, one a storage or open-circuit position and the other a heating or closed-circuit position.

An object of the present invention is to provide a lighter the holder of which has merely a single or storage position for the igniting unit, and, in combination therewith, a means for closing the normally open circuit for energizing the igniting unit, while the igniting unit is in its single or storage position on the holder, and which means is operated by a manually rotatable member separate from the igniting unit.

In the way of carrying out the invention at present preferred, this member is given only a fractional rotation, and preferably carries an exposed finger-piece in the shape of a wing which need be given only a short sweep in order to close the circuit and this by mere brushing engagement against the wing of a person's hand as the latter is moved laterally over the support on which the lighter is mounted. Desirably, also, the wing is so associated with the holder that a hand reached out to move the wing to circuit-closing position naturally also engages the usual withdrawal knob at the outer end of the igniting unit, and thus is guided to the location of the wing by feel instead of sight; and, further, according to the invention as preferably embodied, the fractionally rotatable operating member or shaft which carries the wing, while rotating about an axis exterior to the holder, is coupled to the holder so as to provide with the latter one structure attachable as a single entity to a suitable support, such as the instrument board of an automobile.

Another preferred feature of the invention is the provision of a circuit-closing contact moved with the rotatable shaft to engage a conducting part of the unit when the latter is in storage position on the holder, thereby to close the energizing circuit for the heating element, which contact is so shaped and resiliently biased that in

entering into engagement with the unit it retainingly clasps the latter and is held to such clasp until automatically deformed to move away from circuit-closing position as the result of heat-responsive means functioning when the heating element has attained a predetermined temperature. Preferably, the contact thus behaves because it is a bimetallic thermostat.

With such an arrangement, and with the operating shaft spring-urged toward open-circuit position as a feature also preferably incorporated according to the present invention, an easy sweeping touch of the hand or a finger is all that is required to adjust the lighter for energization of the heating element of the igniting unit, and the only other manipulation required is the subsequent one of manually grasping the knob of the unit to withdraw the same when ready for use.

An advantage of an arrangement such as that just described is the fact that, however deep the igniting unit may be carelessly placed in the holder in returning the unit thereto for storage, the then open energizing circuit may not be unintentionally reclosed by such reinsertion of the unit. At the same time, the manually operated closing means cannot be accidentally placed in circuit-closing position while the igniting unit is out of the holder, in a way to allow subsequent replacement of the unit to inadvertently cause closing of the circuit.

A further feature of the invention as the same is preferably practiced is the provision of a means, conveniently moving with the operating shaft, for locking the igniting unit against premature withdrawal after the circuit has been closed by manually rotating the shaft, until the heating element has been brought to incandescence; with this lock such that any manual pull on the knob of the unit is an attempt to withdraw the same while the circuit is closed will not be transmitted to the bimetallic contact in a way to distort or otherwise injure the same.

Other features and advantages will hereinafter appear.

In the accompanying drawing, illustrating a now favored embodiment of the invention:

Figure 1 is a view thereof showing the holder in axial section and the removable igniting unit partially in axial section and partially in elevation, the section plane being that indicated by the line 1—1 of Fig. 2.

Fig. 2 is a transverse vertical section, taken on the line 2—2 of Fig. 1, with the thermostatic contact in circuit-closing position on the unit but

with such contact as yet undeformed by heat.

Fig. 3 is a view similar to Fig. 2, but showing the thermostatic contact in normal or open-circuit position.

5 Fig. 4 shows the lighter in rear elevation.

Fig. 5 is a front elevational view of the same.

Fig. 6 is a fragmentary detail, this view taken on the line 6—6 of Fig. 2.

As shown in the accompanying drawing, the 10 cigar lighter of the present invention comprises a holding device 10 including a main portion in the form of a cylindrical tube 10' having an externally threaded neck 11 at its front end, lanced out tongues one of which is shown at 12, and 15 a nut or escutcheon ring 13 secured on said thread and engaging the front side of an automobile instrument panel 14 or other suitable support through an aperture 14' in which the front or threaded end of the holder is inserted; the 20 nut 13 when tightened up serving to draw the ends of the tongues 12 against the rear side of the panel 14 and thereby clamp the holder on its support.

Also as shown the holder 10 is one such that 25 the igniting unit, generally indicated at 15, has but a single position in the holder, either for storage of the unit or energization of the heating element 16 thereof. This element is here shown as a spirally wound coil of band-type resistor 30 wire electrically and mechanically connected at its inner end to a stud 17 secured on the unit and similarly connected at its outer end to a cup or hood 18 of conducting material mounted on the unit by way of said stud.

35 In the exemplifying embodiment illustrated, the igniting unit 15, manually withdrawable by its knob 19 when it is on the holder 10 as shown, has, as just stated, but a single position on the holder, and when inserted into the holder by full 40 thrust on the knob 19 is always located as shown in Fig. 1, a shoulder 20 near the base of the knob acting as a stop to prevent too deep insertion of the unit.

Then a contact on the unit, the cylindrical part 45 18' of the cup 18 which encloses the heating element 16, is opposite a cooperant contact 21, here shown as a bimetallic thermostat normally positioned as illustrated in Fig. 3 but manually movable to a clasping engagement with the contact 50 18' as illustrated in Fig. 1 for then closing the only gap in an energizing circuit for the heating element and including the holder and the igniting unit.

The igniting unit 15 illustrated is of the now 55 familiar and approved type, because in the form of a cylindrical plug for endwise insertion in the favored well-type holder shown, and because, in addition to having the characteristics above-mentioned, it includes a main cylindrical body 22 of insulating material and hollowed out to provide a passage 22' all along its length, a lens 23 in the knob 19 and covering the front end of the passage 22', a metal cap 24 threadedly secured on the rear end of said body, at the center of which cap the stud 17 is secured, insulation as indicated at 25 for electrically isolating the stud from the cup or hood 18 and said hood from the cap 24, and matching apertures through the insulation, through the hood where 60 it is engaged by the insulation, and through the cap, so that the glow of incandescence of the heating element will be transmitted through these apertures and cause the passage 22' to act as a light tunnel for permitting such glow to 65 illuminate the lens 23, thus to give visual warn-

ing that the igniting unit is ready for removal from the holder.

The igniting unit 15 has an annular shoulder 26, in rear of which the body 22 is slightly reduced in diameter, and over this last-mentioned length 5 of the body 22 and over a part of the metal cap 24, a metal sleeve 27 is, by forced fit or otherwise, suitably fixed in place on the unit as shown. The wall of the main cylindrical portion of the holder has a plurality of tongues 28 lanced therefrom, these bent and resiliently biased so as to pressingly engage the sleeve 27 of the unit when the unit is positioned as illustrated.

Then the grounded side of the energizing circuit is complete, from the inner end of the heating element 16, to and through the stud 17, the cap 24, the sleeve 27, the holder 10, and the panel 14 grounded to the frame of the car.

10 The present invention provides, in combination with a lighter the holder of which has merely 20 a single or storage position as already emphasized, a means for closing the energizing circuit for the igniting unit while the same is on the holder and which includes a manually rotatable member separate from the igniting unit.

15 As here shown, such member is a shaft 28 manually fractionally rotatable by means of a finger-piece in the form of a depending wing 29 located in such close adjacency to the mouth of the holder 10 that a hand reached out to move 30 the wing to circuit-closing position naturally also engages the knob 19 of the igniting unit, so that the wing may be located by feel instead of sight, and so that at the same time the fact that the unit is in the holder is ascertained.

20 The shaft 28 is wholly exterior to the holder 10, but this shaft is part of a single structural entity including the holder by being journaled near its front end and just back of the point where the wing 29 is made fast thereto, in a 40 hanger 30 constituted by a struck-out portion of the wall of the main cylindrical portion of the holder, and being journaled at its rear end, where its diameter is reduced, in a back plate 31 forming the rear closure of an axially shallow radially 45 enlarged chamber 32 carried by the holder immediately to the rear of the main cylindrical portion 10' thereof which houses the main body of the igniting unit.

25 The chamber 32 has an opening 33 in its bottom 50 extending over the full length of the chamber and as wide as the width of a leaf portion 31a constituting a downward projection from the generally circular main portion of the back plate 31. A front annular wall 34 for the chamber 32 55 and a cylindrical side wall 35 therefor are integral with the main cylindrical portion 10' of the holder. As shown, the wall 35 and the back plate 31 are secured together, by interengagement between the leaf portion 31a of said plate 60 and edge portions of the wall 35 at the opposite sides of the bottom opening 33 in the chamber 32, and by tightly crimped tabs 36 integral with the wall 35 and interlocked with notches 37 cut in the circular edge of back plate 31.

30 Fixed on the shaft 28 is an insulating arbor 38, and fixed on this arbor, as by set screw 39, is a bracket-collar 40, carrying a plate 41 on which is mounted the bimetallic contact 21. A pigtail lead 42, protected by insulation beads 43, 70 is connected at one end to a screw 44 on the bracket-collar, and at its other end to a stud 45 extended through an insulation structure 46 on back plate 31. The stud 45, where projected to the rear of insulation structure, and there 75

carrying an external thread, acts as a binding post for a connection to the live side of the battery or other current source; a current-supplying wire being shown at 47 as carrying a terminal clip 48 secured to the stud 45 by a nut 49.

In order to normally maintain the shaft 28 and the parts carried thereby as in Fig. 3, and to assure return of these parts to the positions of Fig. 3 immediately on manual release of the wing 29 after moving the same from the position of Fig. 3 to that of Fig. 2, a torsion spring 50 is coiled around shaft 28, with one end thereof bent to lockingly engage a recess 51 in the shaft, so that the other end of the spring, bent to pass through a hole 52 in the wall 34 of the holder, is held in such hole. In this normal setting of the parts, it will be observed, the bimetallic contact 21 is protected against accidental engagement with the holder 10 because intercepted by an insulation block 53 suitably fixed in proper place inside the wall 35 of the chamber 32.

The bimetallic contact 21, which is shown as curvilinear, is resiliently biased to elastically yieldable maintenance of this shape, and is bent at its free end to present a ramp-lip 21a. When, with the igniting unit fully inserted in the holder, the wing 29 is moved from its normal position as is Fig. 3 to its circuit-closing position shown in Fig. 3, the contact 21 is swung in the plane of the heating element 16, and as the result of engagement of its ramp-lip 21a with the cooperant cylindrical contact provided by the contact 18' carried by the hood 18, the contact 21 is temporarily slightly spread and then returned to the curvature illustrated as it finally, as shown in Fig. 2, springs embracingly about the contact 18', and impositively seizes the same with a tightness of grasp able to withstand the tension now in spring 50 and tending to return the shaft 28 to the position shown in Fig. 3.

This tension of spring 50 is preferably comparatively light, as an advantageous feature of the invention is the slight force required to fractionally rotate the shaft 28 to close the circuit.

With the parts arranged as in Fig. 2 the closed circuit for the heating element 16, on the live side thereof, includes the wire 47, the stud 45, the lead 42, the metal parts 40 and 41 on the arbor 38, the thermostatic contact 21, and, on the unit, the cooperant contact 18' connected as above to the outer end of the heating element.

A feature of the invention is the provision of a laterally movable contact, and preferably a thermostatic one, for being manually moved toward a cooperant contact to close the energizing circuit for the heating element of the igniting unit. Such a thermostatic contact is conveniently fashioned, as by making the same curved and substantially U-shaped as illustrated, for acting in the manner above-described and to give the advantages already noted. A further advantage is that a bimetallic contact operated according to the principle of operation of the contact 21 does not open the circuit immediately on first deformation of the contact in response to heat emitted by the heating element while being brought to incandescence. The circuit is not broken until the contact 21 snaps completely free of the cylindrical part of hood 18 which acts as the cooperant contact 18', and up to this point and all the while the contact 21 is undergoing greater and greater deformation toward a reshaping thereof to allow it to snap free, its ramp-lip 21a is in circuit-making engagement with the contact 18' because sliding over the same. A

laterally moving contact, moreover, is very practicably operated by a shaft, such as the shaft 28, wholly exterior to the holder; and where a spring, such as the spring 50, is employed for returning the shaft to normal position on predetermined heat deformation of the bimetallic contact, such spring may be located, as in the present case, not only outside the holder but in a location such that heat from the heating element may not anneal or otherwise weaken the same. As will be understood from what has been said in connection with the slight force desirably used in fractionally rotating the shaft 28 to circuit-closing position, it will be understood that the tension of the spring 50 is comparatively delicate and should be maintained more or less exactly as revised; which last might present difficulties if the spring were so placed as to be affected by heat from the heating element.

With the igniting unit 15 in the holder 10, merely a single operation is required to prepare the unit for withdrawal and use, and this is a light flick of a finger tip against the wing 29 applied in the direction of the arrow 29' of Fig. 3. The resulting fractional rotation of shaft 28 causes the energizing circuit for the heating element 16 of the unit to be closed, and impositively held closed, by engagement of the thermostatic contact 21 with the hood 18 as in Fig. 2. The only other operation required, when the unit is ready for use, which readiness is visually signalled by illumination of the lens 23 and audibly signalled by click of the wing 29 when, in returning to normal position, it strikes against a pin 54, is a manual pull on the knob 19 of the unit to withdraw the same from the holder.

Reinsertion of the igniting unit into the holder cannot ever result in accidentally reclosing the circuit, due to the retention of the contact 21 in the position shown in Fig. 3 by the spring 50. Care need not be exercised to insert the unit to a shallow storage position on the holder, as the unit cannot be energized until fully inserted in the holder, and such full insertion is that which the unit is intended to have when placed on the holder merely for storage. However, only when the unit is in such position on the holder may the circuit be closed and held closed after manual release of the wing 29; as, unless the contact 21 is brought into clasping engagement with the unit as shown in Fig. 2, the spring 50 insures return of the contact 21 in the position shown in Fig. 3. Thus the manually operated circuit-closing means cannot be accidentally placed in circuit-closing position while the igniting unit is out of the holder in a way to permit subsequent replacement of the unit to result in inadvertent closing of the circuit.

There is also provided by the present invention a means for locking the ignition unit 15 against premature withdrawal from the holder 10 after the circuit has been closed by manual rotation of shaft 28, until the heating element 16 has been brought to incandescence, thereby to insure that any manual pull of the knob 19 of the unit in an attempt to withdraw the same while the circuit is closed will not be transmitted to the contact 21 in a way to distort or otherwise injure the same. This locking means, as here shown, is partly carried by the shaft 28 and partly carried by the hood 18 of the igniting unit. Referring to Figs. 2 and 6, the upper curved extension 41a of the plate 41 carries a lug or dog 55, which is cleared away from the igniting unit when the parts are arranged as in Fig. 3, but which, until the contact 75

21 returns to the position shown in Fig. 3, is projected, as indicated by dot-and-dash lines in Fig. 1, and also as shown in Fig. 2, to lie over the front annular face of the part of hood 18 directly 5 enclosing the heating element and providing the contact 18'. As shown, the lighter is a self-contained unitary structure, completely assembled as such, except, of course, for the wire 47, when delivered to the customer. Such unitary structure is easily and quickly secured in place on the instrument panel of an automobile, when the latter is cut out to provide, instead of the usual circular aperture, a keyhole-shaped aperture as shown in the drawing. 10 Such aperture, in the panel 14, includes as its main portion the opening 14' aforesaid, this main portion corresponding in diameter to the outside diameter of the cylindrical wall of the main portion 10' of the holder shown in broken lines 15 in Fig. 4, and, as a lesser portion, a downwardly directed extension seen in Fig. 1 and shaped as indicated by the dot-and-dash outline 41b' in Fig. 4.

In order to mount the lighter on the panel by 20 tightening of the nut 13 as hereinabove described, it is unnecessary to disturb the mounting of the wing 29 on the shaft 28. With the igniting unit 25 out of the holder, and with the nut 13 removed, all the parts except the last two mentioned can 30 be brought to relation with the panel 14 as shown in Fig. 1, merely by first canting down the rear end of the holder sufficiently to pass the wing 29 through the keyhole-shaped aperture in the panel and then swinging up the rear end of the 35 holder while moving the same bodily downward somewhat, as the upper part of the neck portion 11 of the holder is passed through the upper part of the aperture in the panel.

Variations and modifications may be made 40 within the scope of this invention, and portions of the improvements may be used without others.

I claim:

1. An electric cigar lighter comprising a holder; an igniting unit having a heating element and 45 storable on the holder but wholly removable therefrom for use; a normally open circuit including the holder and the unit for energizing the heating element; means for closing said circuit comprising a shaft exterior to the holder, a 50 manually operable actuator for the shaft adjacent the unit-receiving end of the holder, a contact on the unit, and a contact operably coupled to the shaft and moved by fractional rotation of the shaft to engage the contact on the 55 unit; and means rendered operative by the movement of said contact for holding the igniting unit against removal while said circuit is closed.

2. An electric cigar lighter comprising a holder; an igniting unit having a heating element and 60 storable on the holder but wholly removable therefrom for use; a normally open circuit including the holder and the unit for energizing the heating element; means for closing said circuit comprising a manually rockable shaft exterior to 65 the holder, a contact on the unit, a cooperant bimetallic contact adapted to claspingly engage the contact on the unit when moved into engagement therewith, and an operative connection between the bimetallic contact and the shaft 70 whereby manual rocking of the shaft closes said circuit by swinging the bimetallic contact, laterally of the direction of movement of the unit for storage on the holder, into engagement with the contact on the unit; and means for urging said shaft to move the bimetallic contact to open- 75

circuit position, said means being rendered operative by the release of the clasping action due to the flexing of the bimetallic contact upon being heated.

3. An electric cigar lighter comprising a holder; 5 an igniting unit having a heating element and storable on the holder but wholly removable therefrom for use; a normally open circuit including the holder and the unit for energizing the heating element; means for closing said circuit comprising a switch including a pair of contacts, one on the unit and one mounted for movement relative to the other, means for moving the movably mounted contact toward the other contact to engage the same and including a 15 manual actuator; one of said contacts being shaped to present a recess and the other being shaped to present a part enterable in said recess, and one of said contacts being resiliently biased to maintenance of its said shape whereby when the 20 contacts engage one clasps the other as an impositive detent therefor a positive detent for engaging the unit to prevent withdrawal of the same from the holder during continuance of said clasp; and means responsive to heat from the 25 heating element and associated with the resiliently biased contact for deforming the same to release such clasp when the heating element attains a predetermined temperature.

4. An electric cigar lighter comprising a holder; 30 an ignition unit having a heating element and storable on the holder but wholly removable therefrom for use; a normally open circuit including the holder and the unit for energizing the heating element; means for closing said circuit comprising a switch including a pair of contacts, one on the unit and one mounted for movement relative to the other, means for moving the movably mounted contact toward the other contact to engage the same and including a manual 35 actuator, one of said contacts being shaped to present a recess and the other being shaped to present a part enterable in said recess, and one of said contacts being resiliently biased to maintenance of its said shape whereby when the contacts engage one clasps the other as an impositive detent therefor; and means normally ineffective but rendered effective by the means for moving the movably mounted contact to establish said clasp for preventing relative movement between the unit and the holder during maintenance of said clasp.

5. An electric cigar lighter comprising a holder; an igniting unit having a heating element and storable on the holder but wholly removable therefrom for use; a normally open circuit including the holder and the unit for energizing the heating element; and means for closing said circuit comprising a switch including a contact on the unit, a movable contact, manually operable 60 means for moving said last-mentioned contact laterally of the holder to engage and grip the contact first-mentioned, said movable contact being a strip bent into the form substantially of a U and having a substantially circularly curved 65 portion adapted to snap into engagement with the contact on the unit, and the contact on the unit being extended laterally thereof and having a substantially circularly curved portion.

6. An electric cigar lighter comprising a holder; 70 an igniting unit having a heating element and storable on the holder but wholly removable therefrom for use; a normally open circuit including the holder and the unit for energizing the heating element; means for closing said circuit 75

- comprising a switch including a contact on the unit, a movable contact, manually operable means for moving said contact laterally of the holder to engage the contact first-mentioned, said movable contact including a resilient jaw to yieldingly grip said first-named contact when moved to circuit-closing position, said movable contact being bimetallic and adapted to release the contact on said unit after a predetermined temperature has been attained by the heating element; and additional detent means for holding the igniting unit against removal from the holder while the contacts are in closed-circuit position.
7. An electric cigar lighter, comprising a holder; an igniting unit having a heating element and storable on the holder but wholly removable therefrom for use; a normally open circuit including the holder and the unit for energizing the heating element; and means for closing said circuit comprising a switch including a contact on the unit, a movable contact, manually operable means for moving said contact last-mentioned laterally of the holder to engage the contact first-mentioned, said movable contact being a strip bent into the form substantially of a U and having a substantially circularly curved portion forming a jaw, the contact on the unit being extended laterally thereof and having a substantially circularly curved portion, said jaw being resiliently biased to have a concave face of its curved portion of less radius than that of the substantially circular curvature of the contact on the unit whereby said jaw yieldingly grips said first-named contact when moved to circuit-closing position, and means being associated with said jaw contact responsive to heat from the heating element for enlarging the radius of its said curved portion when the heating element reaches a predetermined temperature.
8. An electric cigar lighter comprising a holder; an igniting unit having a heating element and storable on the holder but wholly removable therefrom for use; a normally open circuit including the holder and the unit for energizing the heating element; a contact on the unit; a movable contact normally spaced from the contact on the unit which when engaged with the contact on the unit closes said circuit; means separate from said unit operable from the exterior of the holder for moving the movable contact into engagement with the first-mentioned contact, said movable contact being bimetallic and claspingly engaging the first-mentioned contact and being deformable in response to heat from the heating element to cause disengagement of the contacts when the heating element reaches a predetermined temperature; separate means for holding the igniting unit in stored position on the holder while the circuit is closed; and means for automatically returning said movable contact to its normal position on said disengagement of said contacts, said means also releasing the holding means whereby the igniting unit can be removed for use.
9. A cigar lighter comprising a holder; an igniting unit having a heating element and adapted to be supported by the holder in a single position thereon either for storage or for energization of the heating element; a normally open circuit including the holder and the unit for energizing the heating element; means separate from said unit for closing said circuit, said closing means including a manual actuator on the holder and an impositive latch means for the unit rendered operative when the circuit is closed; means responsive to heat from the heating element for releasing said latch means when the heating element reaches a predetermined temperature; and separate means, rendered operative by operation of said manual actuator to close the circuit, for positively detaining the unit in said holder until said latch means is released.
10. A cigar lighter comprising a holder; an igniting unit having a heating element and adapted to be supported by the holder in a single position thereon either for storage or for energization of the heating element; a normally open circuit including the holder and the unit for energizing the heating element; means for closing said circuit only when the unit is in its said single position on the holder, said closing means including an impositive latch means, a manual actuator therefor; means responsive to heat from the heating element for releasing said latch means when the heating element reaches a predetermined temperature; normally inoperative stop means for holding the unit in its said single position but rendered operative by operation of said manual actuator to close the circuit; and means for restoring said stop means to its normal position when said latch means is released.
11. A cigar lighter comprising a holder; an igniting unit having a heating element and adapted to be supported by the holder in a single position thereon either for storage or for energization of the heating element; a normally open circuit including the holder and the unit for energizing the heating element; means for closing said circuit only when the unit is in its said single position on the holder, said closing means including a movable contact and a manual actuator therefor separate from said unit, an impositive latch means for the unit rendered operative when the circuit is closed; means responsive to heat from the heating element for releasing said latch means when the heating element reaches a predetermined temperature; means for automatically moving said manual actuator to circuit-opening position upon release of said latch means, and positive detent means for holding the igniting unit against removal from the holder while said contacts are in closed-circuit position.
12. An electric cigar lighter comprising a holder presenting a well; a plug-like igniting unit having a heating element and inserted in said well but wholly removable from the holder for use; a normally open circuit including the holder and the unit for energizing the heating element; means for closing said circuit including a contact on the unit extended curvilinearly around the same in a plane substantially at right angles to the axis of the unit, a movable bimetallic contact having a strip portion substantially similarly curvilinearly extended in said plane, a manual actuator for closing said circuit by engagement of said contacts and including a shaft journaled on the holder alongside the same, an operative connection between the bimetallic contact and the shaft whereby when the shaft is in normal or circuit-opening position the bimetallic contact is positioned to have the unit clear the same in any position of the unit in the well and whereby on fractionally rotating the shaft in one direction from its said normal position to circuit-closing position the bimetallic contact is engaged with the contact on the unit if the unit is at a predetermined degree of insertion in the well, said bimetallic contact being resiliently biased to a curvature such that it will then impositively clasp the contact on the unit but being deformable

by heat from the heating element to release such clasp when the heating element reaches a predetermined temperature; and a yielding means always tending to restore said shaft to its normal position.

13. An electric cigar lighter comprising a holder; an igniting unit having a heating element and storable on the holder but wholly removable therefrom for use; a normally open circuit including the holder and the unit for energizing the heating element; a contact on the unit; a movable contact normally spaced from the contact on the unit which when engaged with the contact on the

unit closes said circuit; means separate from said unit for moving the last-mentioned contact to circuit-closing position, said last-mentioned contact comprising a bimetallic element adapted to releasably engage the first-mentioned contact 5 upon movement to said closed-circuit position; and means carried by the first-named means and controlled by said bimetallic element for positively retaining the unit in said holder only until said unit has attained a predetermined temperature 10 whereupon the retaining action is withdrawn.

ARTHUR A. JOHNSON.
